(57) **CLAIM**

We claim the ornamental design for a rear axle assembly for a model vehicle, as shown and described.

DESCRIPTION

FIG. 1 is a top, right, front perspective view of a rear axle assembly for a model vehicle;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, right, rear perspective view.

The broken line represents environment only and forms no part of the claimed design.

1 Claim, 6 Drawing Sheets
